CLAIM

The ornamental design for a charger door, as shown and described.

DESCRIPTION

FIG. 1 is a front, top, and left side perspective view of a charger door showing the new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof;
FIG. 7 is a left side elevational view thereof;
FIG. 8 is a first perspective view thereof with the door in a use position;
FIG. 9 is a second perspective view thereof with the door in a use position; and,
FIG. 10 is a third perspective view thereof with the door in a use position.
The broken lines in FIG. 10 show environmental subject matter that forms no part of the claimed design.

1 Claim, 10 Drawing Sheets
